UNITED STATES PATENT OFFICE.

FREDERIK JENSEN, OF ROCHESTER, NEW YORK.

FUEL-TANK FOR INTERNAL-COMBUSTION ENGINES.

1,350,808.

Specification of Letters Patent. Patented Aug. 24, 1920.

Application filed December 19, 1919. Serial No. 346,068.

To all whom it may concern:

Be it known that I, FREDERIK JENSEN, a citizen of the United States, and resident of Rochester, in the county of Monroe and 5 State of New York, have invented certain new and useful Improvements in Fuel-Tanks for Internal-Combustion Engines, of which the following is a specification.

The present invention relates to fuel tanks for internal combustion engines and more particularly to the type in which provision is made for stopping the flow of fuel from the tank when a certain level is reached in order to notify the user that the tank must 10 soon be replenished, an object of this invention being to provide an improved valve which is of simple construction and not liable to get out of order. A further object of the invention is to provide means which 15 will prevent the opening of the tank to refill the same until the valve is shifted to a position where it will cause the flow from the tank to cease before the tank is empty.

To these and other ends, the invention 20 consists of certain parts and combinations of parts, all of which will be hereinafter described, the novel features being pointed out in the appended claims.

In the drawings:

30 Figure 1 is a fragmentary view of the tank in plan showing the means for locking the tank closure against removal in the position which it occupies when the valve is shifted to the position which causes the tank 35 to cease to flow at a certain level;

Fig. 2 is a view similar to Fig. 1 showing the closure locking means in the position which it occupies when the valve is turned to the position to empty the tank;

40 Fig. 3 is a fragmentary view partially in section showing the connection between the valve and the tank closure;

Fig. 4 is a detail view of the shaft which connects with the valve member;

45 Fig. 5 is a detail view of the valve member;

Fig. 6 is a view partially in section of the valve casing;

50 Fig. 7 is a side view of the valve casing;

Fig. 8 is a top view of the valve casing; and

Fig. 9 is a detail view of the guide for the rod which prevents the removal of the closure.

55 Referring more particularly to the draw-

ings 1 indicates the fuel tank which has an outlet pipe 2, in this instance threaded at its upper end in a bushing 3 secured to the bottom of the tank. The outlet pipe may be internally threaded to receive the lower 60 threaded end 4 of a valve casing member 5. This valve casing member preferably is provided with a vertical passageway 6 extending therethrough and is also provided with a lateral port 7 leading to said passageway. 65 In this valve casing operates a valve member 8, this valve member being preferably provided with a vertical passageway and with two lateral ports 9 and 10, one of said ports being in a higher plane than the other, the 70 port 9 being elongated and receiving a projection 11 in the form of a screw passed through the valve casing and acting to limit the rotary movement of the valve member 8 by co-operating with the ends of the slot, 75 this projection at the same time serving to support the valve member 8 in the valve casing 5. A rod 12 may be secured at 13 to the upper end of the valve member 8 and may project upwardly through the top wall 80 of the tank 1, an arm or operating lever 14 being secured by a nut 15 to the upper screw threaded end of this rod 12. Through this arm the valve member 8 may be moved to open and close the port 7.

It is preferred to lock the closure 16 for the tank 1 against removal until the valve member 8 has been moved to close the port 7 so that it will be impossible for the user of the tank to fill the same and then neglect 90 to close the lowermost discharge opening. To this end, a bar 16^a may be pivotally connected at 17 to the arm 14 and move in a guideway 18. This guideway may be formed by a single piece of metal secured to the 95 top of the tank and bent between its ends to provide two loops 19 forming the guide 18 between them, the top of the guide being closed by one end 20 of the metal which is extended over the guideway and rests upon 100 the upper ends of the two loops 19, the portion 20 being resilient and bearing on the rod 16^a to produce friction thereon.

From the foregoing it will be seen that there has been provided in combination with a fuel tank, a valve in which a rotary valve member is provided with two ports, one of which is located above the other, the lower port being adapted to be brought into and out of register with the port in the valve 110

casing. There has also been provided a construction in which a projection coöperates with the lower part in the valve member to limit the rotary movement of the 5 valve member. The invention also prevents the opening of the tank until the lower discharge opening of the valve is closed so that it will be impossible for the user of the tank to fill the same without first closing 10 the lower discharge opening.

What I claim as my invention and desire to secure by Letters Patent is:

1. In combination with a fuel tank for internal combustion engines having an outlet; a rotary valve for controlling such outlet comprising an open ended casing member having a lateral port, a valve member mounted to turn in said casing projecting from the upper end of the casing, having 15 its lower end opening to the open lower end of the casing in all positions of the valve and having also two lateral ports, one above the other, the lower port being adapted to be brought into and out of register with 20 the port in the casing member upon the rotation of the valve and means for limiting 25

the rotary movement of the valve and preventing the longitudinal movement thereof.

2. In combination with a fuel tank for internal combustion engines having an outlet; 30 a valve for controlling such outlet comprising a casing member having a lateral port, a valve member mounted to turn in said casing and having two lateral ports, one above the other, the lower port being 35 adapted to be brought into and out of register with the port in the casing member, and a projection within the casing member, operating in the port of the valve member to coöperate with opposite end of the port 40 in order to limit the movement of the valve member in said casing member.

3. In combination with a tank for internal combustion engines having an outlet, and an inlet, and a closure for the inlet; a rotary 45 valve for controlling such outlet, having a shaft extending to the exterior of the tank, an arm on said shaft, and a rod eccentrically connected to said arm and adapted to be moved to prevent the opening of the closure 50 to the tank when the valve is in one position.

FREDERIK JENSEN.
